CLAIM

We claim the ornamental design for a paper support for multi-function printer, as shown and described.

DESCRIPTION

FIG. 1 is a front perspective view of a paper support for multi-function printer, showing our new design; FIG. 2 is a front view thereof; FIG. 3 is a rear view thereof; FIG. 4 is a left-side view thereof; FIG. 5 is a right-side view thereof; FIG. 6 is a top view thereof; FIG. 7 is a bottom view thereof; and, FIG. 8 is another front perspective thereof, in which a multi-function printer in broken lines is provided to illustrate an example environment.

The broken lines illustrating portions of the paper support for multi-function printer are for environmental purposes only and form no part of the claimed design. The dot-dash lines in the figures represent an unclaimed boundary line and form no part of the claimed design.

The oblique lines in the drawings represent transparency.
